UNITED STATES PATENT OFFICE

ARTHUR HOHMEISTER, OF CINCINNATI, OHIO, ASSIGNOR TO THE JOHN DOUGLAS COMPANY, OF CINCINNATI, OHIO, A CORPORATION OF OHIO.

BALL-COCK.

1,338,179.

Specification of Letters Patent.

Patented Apr. 27, 1920.

Application filed November 23, 1917. Serial No. 203,498.

To all whom it may concern:

Be it known that I, ARTHUR HOHMEISTER, a citizen of the United States of America, and resident of Cincinnati, in the county of 5 Hamilton and State of Ohio, have invented a new and useful Improvement in Ball-Cocks, of which the following is a specification.

An object of my invention is to produce 10 an improved ball cock for flush tanks which will operate with less noise than other ball cock constructions known to me.

A further object is to produce an improved ball cock construction in which increased efficiency of closing action is attained over other ball cock constructions 15 known to me.

A further object is to produce a ball cock 20 of simple, reliable and cheap construction, in which a minimum number of working parts are present and which may be quickly taken apart and put together to effect repairs.

These and other objects are attained in 25 the ball cock described in the following specification and illustrated in the accompanying drawing, in which:

Figure 1 is a sectional view of a flush tank having a ball cock embodying my invention 30 mounted therein.

Fig. 2 is a longitudinal sectional view through a ball cock embodying my invention.

Fig. 3 is a fragmental longitudinal sectional view showing the parts in different 35 positions from those illustrated in Fig. 2.

Fig. 4 is a fragmental sectional view of 40 my improved ball cock taken on the line 4-4 of Fig. 1, the parts being shown in positions to permit the entrance of water to a flush tank containing the ball cock.

My improved ball cock consists of a body 5 having a casing 6 at the upper end of a water admission standard 7, the interior of 45 the casing forming a distribution chamber 8 into which water from standard 7 enters, a valve seat 9 at the upper end of standard 7 and within chamber 8, a cap 10 adapted to close the chamber, a flexible diaphragm 50 11 located between the cap and casing, a diaphragm operating plunger 12, a plunger operating lever 13, and discharge pipes 14 and 15 located in the bottom of the casing 6.

Standard 7 is secured upon the bottom of

the flush tank by means of the usual fastening means 16 which also connects the water pipe 17 with the standard 7. Cap 10 screws onto casing 6 and clamps diaphragm 11 at its periphery against the top edge of casing 6. Valve seat 9 is provided with a concave or countersunk upper surface 18 against which the diaphragm is pressed by plunger 12. The lower end of plunger 12 is convex so as to cause diaphragm 11 to seat firmly against and into the valve seat. The upper end of plunger 12 is of uniform diameter and reciprocates within a guide 19 formed on the top of cap 10. Plunger operating lever 13 is pivotally mounted at a point 20 upon lugs 21 on the top of guide 19 and is provided with a plunger operating end 22 which is located at an angle to the main portion 23 of lever 13. In a lug 31 formed on lever 13 adjacent to pivot point 20, is mounted a set screw 32 which is adapted to be adjusted to engage guide 19 and to limit the downward movement of float stem 24 55 and the float attached thereto. This is for the two fold purpose of limiting the opening movement of diaphragm 11 so that it may be adjusted for varying water pressures, as well as for the purpose of preventing the interference of float 25 and float stem 24 with the operation of release valve 29. When the water pressure is high the set screw 32 is adjusted to cause lever 13 to 60 permit of but slight movement of plunger 12 and consequently but slight opening movement of diaphragm 11. Under low water pressure the screw may be adjusted to 65 permit of greater opening movement of diaphragm 11. To main portion 13 the stem 24 of ball float 25 is attached in the usual manner. From the bottom of casing 6 a branch channel 26 is provided, a small pipe 70 27 being attached thereto and having its upper end located in an overflow pipe 28, so as to provide for the "after-fill" of the bowl as is usual. I have disclosed the usual form of flush release valve 29 and operating mechanism 30 which needs no detailed description.

In describing the operation of my improved construction, the tank will be assumed to be empty. The water entering standard 7 passes through seat 9, engages diaphragm 11 and after distributing itself throughout chamber 8, the discharge is ef- 75 80 85 90 95 100 105

- fected through pipes 14 and 15 from which it is discharged beneath the surface of the water remaining in the tank. This results in absolutely noiseless discharge of water 5 from the valve. As the tank gradually fills, the float rises and causes lever 13 to press upon plunger 12, thereby flexing diaphragm 11 and causing it to be pressed against seat surface 18 to cut off the water. During the 10 time water is being admitted to the tank, the bowl is being refilled with fresh water through pipes 27 and 28 and as soon as the diaphragm engages surface 18, the "after-
fill" ceases.
- 15 It will be seen that in my improved construction I have devised a ball cock which is of the most simple design, which may be quickly repaired, and which is capable of less noisy and more reliable operation than 20 other ball cocks known to me.

Having thus described my invention, what I claim is;

A ball cock comprising a shallow distribution chamber having in its bottom an admission port and discharge ports, a concave 25 valve seat surrounding the admission port, a flexible diaphragm forming the top of the distribution chamber, a cap covering the distribution chamber and having a guide collar in alignment with the valve seat, a 30 plunger in the guide collar and having a convex face, a lever adapted to reciprocate the plunger and a float attached to the lever.

In testimony whereof, I have hereunto subscribed my name this 21st day of November, 1917.

ARTHUR HOUIMEISTER.
